WALL DRYING RACK

William J. Irwin, Concord, N. H.

Application December 20, 1954, Serial No. 33,608

Term of patent 14 years

(Cl. D49—1)

FIG.1

FIG.2

FIG.3

FIG.4

FIG.6

FIG.5

Fig. 1 is a plan view of a wall drying rack showing my new design;

Fig. 2 is a view in rear elevation thereof;

Fig. 3 is a view in side elevation thereof looking from in a direction beneath Fig. 1;

Fig. 4 is a view in front elevation thereof looking from the left of Fig. 3.

Fig. 5 is a section thereof on line 5—5 in Fig. 1; and

Fig. 6 is a view in side elevation similar to Fig. 3 but showing the rack in folded position.

I claim:

The ornamental design for a wall drying rack, as shown.
